UNITED STATES PATENT OFFICE.

VICTOR C. HUNTINGTON, OF BELOIT, WISCONSIN, ASSIGNOR TO FAIRBANKS, MORSE & CO., OF CHICAGO, ILLINOIS, A CORPORATION OF ILLINOIS.

WASHING MACHINE.

Application filed July 22, 1925. Serial No. 45,283.

My invention relates to washing machines and more particularly to improvements in washing machines of the dolly type.

The usual types of washing machines are classifiable according to the relative action of the dolly upon the fabrics and upon the liquid, respectively. In the first class, machines having a peg type of dolly effect merely a swirling movement of fabric through the liquid, resulting in excessive strain and wear in the cloth being washed. In the second class, the result is effected primarily by agitation of the liquid. Familiar examples of this class are found in the vacuum cup machines, and in those utilizing the capillary effects common to the old fashioned scrubbing board. A third class of machine combines the operations of the preceding types. The cylinder machines, which lift the fabrics and drop them back into the liquid, are good examples of this third or combination class. It is evident that each of these types is peculiarly adapted to the most efficient washing of only certain restricted classes of materials.

The object of my invention is to provide agitating means which comprises a novel form of removable, invertible agitator and which may be adjusted in its position with respect to the materials to be washed, thereby providing in one machine, means for washing most efficiently any type of fabric.

Another object is to provide an agitator with its drive and mounting which cannot tear the cloth being washed.

Further objects and advantages of my invention will appear from the drawings and description thereof as hereinafter set forth.

Although my invention consists largely in the construction and arrangement of parts hereinafter described and particularly pointed out in the claims, yet I do not limit my invention to the precise form or construction of parts shown or the several parts thereof, inasmuch as various alterations may be made without changing the scope of my invention. In the drawing, Fig. 1 represents a top view of the operating dolly of the washing machine. Figs. 2, 3, and 4 show the dolly in various operative positions.

Referring by numerals to the drawings, the tub-base 10 preferably rests upon a sub-structure made of angle bar or other suitable material. The tub is preferably composed of a heavy sheet metal body 11 which

may be of any desirable shape and which is preferably provided with an inwardly extending turned-over upper edge 11' and a flange 10' on its lower edge. Tub body 11 with its turned over edge 11' and flange 10' may be readily formed from a flat sheet of material, thereby providing ease and economy in manufacture. Tub base 10, which may be die formed, is preferably united to the inside surface of flange 10' by a welded or other joint in such a manner that the inside surface of the tub structure presents no ragged edges, seams or projections. This inside surface is preferably tinned or otherwise coated, affording a rust proof surface, thus permitting the use of steel or other comparatively rigid material in the tub construction, and which coating material will further provide a means of filling any interstice which may exist at the tub joints. By the use of this type of joint, the gauge of the sheet metal is not limited as in the usual constructions using double seam joints, or in the case of forming the tub by spinning or other methods. Preferably integral with the base 10 is the agitator well or pedestal 13 which may be attached in any suitable manner and is preferably centrally situated therein. Connection with the driving mechanism is preferably effected through well 13 by means of an agitator sleeve 14. This latter is preferably rotatably mounted on the stationary agitator well or pedestal 13 and rotates on bearings 15 and 16 which may be of any suitable type. The sleeve 14 preferably integral with the

base 10 is the agitator well or pedestal 13 which may be attached in any suitable manner and is preferably centrally situated therein. Connection with the driving mechanism is preferably effected through well 13 by means of an agitator sleeve 14. This latter is preferably rotatably mounted on the stationary agitator well or pedestal 13 and rotates on bearings 15 and 16 which may be of any suitable type. The sleeve 14 preferably extends the full length of its support to the bottom of the tub so that in rotation there is no tendency for the clothes to tear because of relative movement between the sleeve and well. The lower end 14' of the sleeve 14 is preferably flared to divert fabrics from the center to the sides of the tub and thus provides a natural course of movement of both clothes and water. The agitator 17 is preferably mounted on agitator sleeve 14 and in such a manner as to be driven by it and to be easily lifted from the sleeve to permit inversion of position of the agitator and its removal whenever necessary. The agitator 17 preferably consists of a disc-like structure, an approved form of which is shown in the drawings. 18 represents a preferable form of relatively thin blades on one operating surface or face of the agitator and 19 represents a preferable form

of relatively angular projections on the reverse surface. When large heavy fabrics are to be washed, the blades 18 are preferably placed upon the top of the material, giving agitation of both cloth and liquid. If heavy, small piece fabrics are in the machine, the agitator is lifted from the sleeve and replaced with its reverse projections 19 downward, providing only a slight movement of materials sufficient to change their respective positions, and an easy water agitation. Besides the control of process attained by inversion of the operating faces of the agitator with respect to the material to be washed, it may be positioned for beginning the washing process either in the bottom of the receptacle, or at some height above the bottom as will be determined by the nature and amount of material to be washed. If the agitator be left in the bottom of the receptacle with its blades 18 upward and the materials immersed above it, only liquid agitation results. This latter arrangement is best suited to light delicate fabrics. The three suggested positions of the agitator 17 with respect to the materials to be washed are shown in Figs. 2, 3 and 4 respectively, the agitator being supported above the bottom of the tub, in certain cases, by the materials being washed. In Figs. 3 and 4 the agitator is shown in the position which it would occupy when resting upon the material to be washed. Other combinations of agitator design and position may be used.

While I show the projections and blades on the agitator surfaces as being at approximately right angles to these surfaces, and parallel to or at right angles to each other, the angle between said blades and said surfaces, or between different blades, may be varied in any way. Further these projections or blades may be either flat or cambered. Holes 20 are preferably provided in the agitator to produce a better circulation and agitation of liquid, and to permit passage of the liquid through the agitator.

The agitator 17 and sleeve 14 are preferably given an oscillating movement by means of shaft 21, preferably to the upper end of which sleeve 14 is secured by a pin 36, or by a nut or other means. Below the tub on shaft 21 is preferably fitted some suitable type of clutch (not shown) actuated by a clutch control, preferably permitting the engagement or disengagement of a pinion

with a rack of suitable type by the reciprocation of which the shaft is given an oscillating movement.

I claim:

1. In a machine for washing fabrics, an invertible agitator disk, having a plurality of operating faces, each of said faces being adapted for a predetermined use. 60

2. In a washing machine, a removable invertible agitator disk, having a plurality of operating faces, and means whereby said faces may be adjustably positioned with respect to the material to be washed. 65

3. In a washing machine, a removable invertible agitator disk, having relatively flat angular projections on one face thereof and relatively thin blades on another face thereof. 70

4. In a washing machine, a removable invertible agitator disk, having relatively flat angular projections on one face thereof and relatively thin blades on another face thereof, and means for adjustably mounting said agitator whereby said projections and blades 80 may be selectively positioned with respect to the material to be washed. 75

5. In a washing machine, a container, an agitator sleeve adapted to be movably mounted within said container, and a removable invertible agitator disk, having vertically opposed impelling members and adapted to be adjustably positioned on said sleeve. 85

6. In a washing machine, a tub, a pedestal 90 adapted to be mounted within said tub and attached thereto, an agitator sleeve adapted to be rotatably mounted on said pedestal, and a removable invertible agitator disk comprising a variety of impelling means and 95 adapted to be adjustably positioned on said sleeve and to rotate therewith.

7. In a washing machine, a tub having an opening through the bottom thereof, a hollow pedestal adapted to be mounted within 100 said tub over said opening, a shaft adapted to operate through said opening and pedestal, an agitator sleeve adapted to be removably positioned about said pedestal, a bearing between said sleeve and said pedestal, connecting means between said shaft and said sleeve, and a removable invertible agitator disk, having agitating elements on opposite faces, and adapted to be adjustably positioned on said sleeve and to rotate 110 therewith. 105

VICTOR C. HUNTINGTON.
